REED FOR A REED SWITCH

Bernard Edward Shlesinger, Jr., 9411 Macklin Court,
Alexandria, Va. 22309

Filed July 9, 1974, Ser. No. 486,893

Term of patent 14 years

Int. Cl. D13—03

U.S. Cl. D26—13

Fig. 1

Fig. 3

Fig. 4

Fig. 2

Fig. 5

Fig. 7

Fig. 6

FIG. 1 is a top plan view of a reed for a reed switch showing my new design;

FIG. 2 is a front side elevational view thereof;

FIG. 3 is a left side elevational view thereof;

FIG. 4 is a right side elevational view thereof;

FIG. 5 is a top plan view of a modified form of the reed described in FIG. 1 showing my new design;

FIG. 6 is a front side elevational view thereof;

FIG. 7 is a right side elevational view thereof.

The bottom plan views opposite to the top plan views of FIGS. 1 and 5 are identical to these respective figures.

The rear side elevational views of the reeds shown in FIGS. 1 and 5 are mirror images of FIGS. 2 and 6 respectively.

I claim:

The ornamental design for a reed for a reed switch, as shown and described.
